UNITED STATES PATENT OFFICE.

WESTFIELD H. KEILER, OF WATERTOWN, NEW YORK.

FUEL-CONSERVING DEVICE FOR LOCOMOTIVES.

Application filed January 30, 1925. Serial No. 5,854.

To all whom it may concern:

Be it known that I, WESTFIELD H. KEILER, a citizen of the United States, residing at Watertown, in the county of Jefferson and

5 State of New York, have invented new and useful Improvements in Fuel-Conserving Devices for Locomotives, of which the following is a specification.

This invention relates to a fuel saving device for locomotives, and contemplates a structure for regulating the draft when the volume of steam exhausted is reduced as the result of shortening the strokes of the valves, thus preventing some of the fuel and 15 smoke from being expelled through the smoke stack without having had time to burn.

More specifically stated, the invention comprehends the use of a device adapted to 20 be arranged above the exhaust nozzle of the engine, only when the volume of steam exhausted has been reduced as above stated, the device retarding and spreading the steam to cause it to completely fill the smoke 25 stack, with a view of providing for a better vacuum, and a consequent increase of the draft in the fire box, thus allowing the fuel to be consumed moderately and without any waste by having the fuel substantially 30 expelled through the smoke stack before being burnt.

The nature and advantages of the invention will be better understood when the following detailed description is read in connection with the accompanying drawings, 35 the invention residing in the construction, combination and arrangement of parts as claimed.

In the drawings forming part of this application, like numerals of reference indicate similar parts in the several views, and 40 wherein:

Figure 1 is a side elevation of a locomotive equipped with the invention.

45 Figure 2 is a sectional view taken on line 2-2 of Figure 1, looking in the direction of the arrow.

Figure 3 is a plan view of the invention showing normal positions of the device for 50 retarding the exhaust.

Figure 4 is a view taken at a right angle to Figure 3.

55 Figure 5 is a detail view partly in section showing the relation of the draft device with the exhaust nozzle of a locomotive.

Figure 6 is a detail view of the means utilized for holding the sliding members immovable when arranged above the exhaust nozzle for use.

Referring to the drawings in detail, A indicates a locomotive of well known construction and wherein B is the exhaust nozzle while 10 represents the table plate upon which the exhaust nozzle is supported. 60 This nozzle is of course arranged directly beneath the smoke stack 11, and is for the purpose of preventing the smoke and part of the fuel from being taken from the fire box and expelled through the smoke stack, by a forced draft, but I have devised the 65 present invention, which is designed to regulate the draft with a consequent saving of fuel in the manner to be presently described.

The invention comprises a frame made up 70 of spaced U-shaped members 12 which are suitably spaced apart, and terminally secured in any suitable manner as at 13' on to the table plate 10. The members 12 are arranged at the opposite sides of the exhaust

nozzle B, and mounted to slide on this frame 75 are what I term smoke retarders and spreaders which are adapted to be singly placed directly above the exhaust nozzle B for use.

Each of the members just referred to include cross rods indicated at 13 and 14 respectively, and these rods are substantially 80 V-shaped as shown in Figure 4 with each rod 13 formed with a depression at the apex thereof to receive the adjacent part of the rod 14 at the point where these rods are crossed.

The terminals of the rod 13 are connected to cross pieces 15 which are mounted for sliding movement on the members 12 of the frame above described, while 85 the terminals of the rod 14 are also mounted for sliding movement upon the members 12.

In other words, the cross members 15 together with the rods 13 and 14 respectively 90 constitute a unit which is mounted for sliding movement longitudinally of the frame made up of members 12, and these units are normally arranged adjacent the ends of said frame as clearly shown in Figure 3. The

only difference between the sliding units is that the unit at one end of the frame is 95 made up of rods of greater diameter than the rods of the other unit, so that either unit can be used depending upon the volume

of steam being exhausted through the nozzle B. Manifestly, the unit made up of 100

105 rods of greater diameter will be used when the volume of steam exhausted is 105

110 greater than the volume exhausted when the unit made up of rods of smaller diameter is used.

larger rods 13 and 14 will retard the steam and expel the latter to a greater extent than the unit made up of the thinner rods.

As above stated, these units are normally arranged at opposite sides of the exhaust nozzle B, and are adapted to be singly positioned above the nozzle to retard the steam emitted therefrom, and at the same time expel the steam in a manner to cause it to completely fill the smoke stack 11 with a consequent increase in the draft both in the smoke stack and the fire box. Each unit has secured thereto a substantially Y-shaped bracket, the branches 16 of which are secured to said unit, while the stem 17 slides through an opening in the adjacent side of the locomotive as clearly shown in Figure 2. Projecting from each side of the locomotive is a bracket 18 which has journalled therein a shaft 19, the terminals of which are offset as indicated at 21 and 22 respectively. One end 21 of the shaft is connected with the stem 17 of the Y-shaped bracket, while the other end of the shaft is connected with an operating rod 23 which extends the length of the locomotive and connected with a hand operated lever 24. As shown in Figure 1, each lever 24 is adapted to move along the segment 25 with which a pawl 26 cooperates to hold the lever in any given position. Consequently, either unit can be moved to its active position above the exhaust nozzle B, and when either unit is called into use, the other unit in its normal position constitutes a stop to limit the movement of the particular unit called into use so that said unit will be properly located above the exhaust nozzle B for the purpose stated.

Each unit is loosely supported upon the frame members 12, so that they can be readily and easily shifted into their active or inactive positions, inasmuch as the parts are not at any time lubricated; thus necessitating a loose fit. However, after each unit is arranged above the nozzle B to maintain said unit fixed with relation to the frame 12, so that it cannot be displaced or vibrated by the influence of the steam passing from the nozzle B, with this object in view, I preferably make use of a pair of weighted members 27 which are suspended from resilient elements 28 of the configuration shown in Figure 6, and which elements 3 are mounted as shown in Figures 3

and 4, so that the weights 27 are normally disposed above the adjacent sides of the sliding units above described. Each of the sides 29 of these units are constructed of table or wedge shaped members, so that as the units are brought into their active positions directly above the nozzle B, the wedge shaped members 29 pass beneath the weights 27 which engage the members 29 in a manner to hold the unit fixed relatively to the frame 12.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

1. In combination with a locomotive having an exhaust nozzle and a smoke stack, of a draft regulating device comprising a frame arranged within the boiler of the locomotive, units mounted for sliding movement on said frame, and adapted to be singly arranged above the nozzle for use, each unit being designed to retard and spread a reduced volume of steam emitted from the nozzle, to cause said steam to fill the smoke stack with a resultant increase of draft therein, means for singly operating said units, and means automatically engaging said units for holding the latter fixed relative to said frame when arranged above said nozzle.

2. In combination, with a locomotive having an exhaust nozzle and a smoke stack, a draft regulating device comprising a frame arranged within the boiler of the locomotive, units mounted to slide on said frame, and adapted to be singly arranged above the nozzle for use, means for singly operating said units, each unit including cross rods arranged to retard and spread the reduced volume of steam emitted from the nozzle, and thus cause said steam to fill the said stack to increase the draft therein, and means automatically engaging said units and adjusting itself thereto, for holding the units fixed relative to said frame when in position for use.

In testimony whereof I affix my signature.
WESTFIELD H. KEILER.
